IRVING C. JENNINGS, OF SOUTH NORWALK, CONNECTICUT, ASSIGNOR TO NASH ENGINEERING COMPANY, OF SOUTH NORWALK, CONNECTICUT, A CORPORATION OF CONNECTICUT

CENTRIFUGAL WATER PUMP

Application filed June 15, 1923. Serial No. 645,661.

This invention relates to mechanism for pumping water including a centrifugal pump and its structural combination with a motor for driving it. It is intended and adapted by 5 the structural relations and connection between the motor and pump to produce a device occupying a minimum amount of space, avoiding any possible disarrangement of or trouble with the drive connection, making it 10 possible to easily separate the pump and motor, making it possible to dispense entirely with supporting bearings for the drive shaft in the pump, providing for the escape of any air which may enter the pump housing and 15 preventing it from entering the intake of the impeller, maintaining the impeller in hydraulic balance and permitting easy access to and removal of the impeller without disconnecting any piping. The novel features will 20 be understood from the following description and claims taken with the drawing.

In the drawing:

Fig. 1 includes a side view of the motor and its connection to the pump, the pump and 25 a part of the supporting base being shown in vertical longitudinal section;

Fig. 2 is a vertical cross section on the line 2—2 of Figure 1;

Fig. 3 is a cross section on the line 3—3 of 30 Figure 2;

Fig. 4 is an end view of the device looking from the right in Figure 1; and

Fig. 5 is a cross section of the centrifugal pump on the line 5—5 of Fig. 4.

In Figure 1 of the drawings there is shown a motor 10 which may be of any known kind but is preferably an electric motor. It is mounted on a supporting base 11 and is secured in fixed position on that base by bolts 35 12 and 13 passing through the feet 14 and 15 integral with the motor frame, the bolts extending through spacing blocks 17 and 18 and entering a fixed part of the supporting base 11. It will be noted that the supporting 40 base 11 comprises a bottom wall 19 and marginal walls 20 and 21 projecting upwardly from said bottom wall. These marginal walls are of uniform height throughout most of the length of the supporting base but the side 45 walls 21 extend upwardly to a greater height 50 walls 21 extend upwardly to a greater height

at 22 at the end next to the pump. The wall 23 next to the pump is substantially the same height at its ends as the adjacent portions of walls 21 but its upper edge curves downwardly on the arc of a circle between the points 55 24 and 25 near its ends, as shown by dotted line 76 in Figure 4. The supporting base 11 is adapted to rest on and be secured to some other fixed support and for this purpose it has a downwardly extending portion 26 at 60 one end having a horizontal flange 27 thereon provided with bolt opening 28. The other end of the base 11 is provided with a downwardly projecting portion 29 but this projecting portion does not extend downward 65 as far as the one at the other end and is for the purpose of attaching a part of the pump mechanism. The motor 10 has supporting bearings in the casings 30 and 31 for the drive shaft 32 which extends through the 70 motor and projects a material distance beyond the casing 30 at the end of the motor. The casings 30 and 31 carrying the bearings for the shaft are of course rigidly connected to the main housing of the motor. The present invention does not reside in the structural features of the motor itself but does include the provision of the projecting end portion 75 of the drive shaft 32 and the means for connecting it to the water pump and the co-operating means for maintaining the water 80 pump and motor in proper fixed relation.

As will be seen by reference to Figure 1 a centrifugal pump 33 is detachably secured to the end of the supporting base 11 close to 85 the motor 10 and with the axis of its impeller in line with the axis of the shaft 32 of the motor. The housing of the pump includes two main portions having their parts made integral. One of those portions may be called 90 for convenience the volute casing since it contains the volute passageway and impeller and it also includes all pipe connections, the opening through which the drive shaft enters and an integral downwardly extending base portion for attaching it to the end of the base 11 in such position as to support that base when placed on any other supporting surface. As 95 will be seen by reference to Figure 2 the volute casing 34 has a radially projecting por- 100

tion 35 at its lower portion on one side forming a chamber 36 extending part way around the circumference of the volute and having a tubular inlet portion 37 provided with a flange 38 adapted to be connected to the inlet pipe. One wall of chamber 36 which is in a radial plane has an opening 39 in it at the margin of the volute casing for the purpose of permitting the incoming water to pass into a chamber in the other portion of the pump constituting its head closure, as will be later explained. An outlet or discharge pipe connection 40 of the usual form is located at the lower part of the volute casing practically in line with the inlet pipe connection, as shown in Figure 2. The integral head portion 41 embodies the end wall of the pump housing and the adjacent side wall 42 of the impeller casing spaced apart and forming a water chamber between them and having a marginal flange 43 which fits the outer surface of the volute casing which is in a radial plane; the said flange extending throughout the circumference of the head portion. Said flange and the end closure of the head portion are formed with a portion extending outwardly at that part of the circumference where the inlet chamber 36 is located on the volute casing, as shown in Figures 3 and 4, and this extension has an opening 44 corresponding to the opening 39 from the chamber 36 so that the incoming water may enter the chamber 45 in the head portion. The pump casing has an outwardly projecting portion forming a passageway 46 around the upper portion of the volute casing (see Fig. 1) and this passageway, at its central top portion has a vent pipe connection 47 for air, and extends radially inwardly on the side of the volute casing next to the motor 10 forming a chamber 49 at the central portion around the opening 48 for the drive shaft. The head portion 41 has an upwardly projecting portion 50 with one side in contact with the side of the projection on the volute casing forming passageway 46 and having an opening 51 corresponding to the end of the passageway for the escape of air from the head portion. The head portion is detachably connected to the volute casing by studs 52 passing through the flange 43 at different points around the circumference and it will be noted that this head portion may be easily removed by releasing the stud connections and thus expose the impeller and interior of the volute casing for cleaning or repairs.

The shaft for driving the impeller 53 of the pump according to the present invention is in alignment with and rigidly connected to the projecting end portion of the shaft 32 of the motor and may be integral therewith but is preferably separable therefrom. As shown in Figure 1, it consists of a stub shaft 54 extending through the opening 48 in the pump casing and having the impeller 53 secured to its inner end the hub portion 55 of

the impeller being held in place by a shoulder 56 formed by a reduction in diameter of the end of the stub shaft and a screw threaded nut 57 on the end of the shaft, which nut may be turned to clamp it in position. This stub shaft as shown has a cylindrical socket 58 in its outer end, illustrated in dotted lines in Figure 1, in which the projecting end portion of the shaft 32 closely fits. The stub shaft is rigidly connected to the projecting portion of the motor shaft by suitable means such as a screw 59 passing through it and engaging the shaft 32. In these cases where the projecting portion of the shaft is made with a separate stub extension instead of integral, it is necessary that the connecting joint be tight and rigid so that it will have practically the effect of an integral extension so that the shaft will serve as a support for the impeller in the pump housing and will be perfectly steady. By thus supporting the impeller by the drive shaft of the motor it is not necessary to provide the pump housing with any substantial bearing support for it since the pump housing is supported in such position that the shaft will turn freely in the opening 48 in its adjacent wall. The outer wall 60 forming the passageway 46 and the chamber 49 around the drive shaft is provided with a cylindrical portion 61 with an inturned end 62 forming a stuffing box around the shaft for packing rings 63 and 64. A gland 65 having a flange 66 may be operated to compress the packing by means of studs 67. A lantern gland 68 may be used in the packing and connected to the volute by a pipe 69 to water seal the stuffing box (see Fig. 5). This tends to prevent air from entering the pump housing but if any should leak in it would pass upwardly through the passageway 46 to the outlet pipe connection 47 and any air which may be drawn into the pump through the inlet connection will also rise to the top of the casing and escape through the opening 51 in the head portion and the vent pipe connection 47. The passageway 46 and chamber 49 connected with the water chamber in the head portion 41 serve the additional purpose of maintaining the impeller in hydraulic balance, since it provides for equal water pressure on both sides of the exposed hub portion of the impeller. The water from the inlet fills the chamber 45, and passing through the opening 51 and passageway 46, fills chamber 49, so that these chambers are both constantly full of water. It will be noted that the hub portion of the impeller forms part of the inner wall of the water chamber 49.

The supporting base for the pump which as above stated is integral with the volute portion includes a vertical plate-like portion 73 which fits the outer face of the wall 23 of the base portion 11 and a horizontal plate-like portion 71 projecting therefrom at its lower

edge and having thickened end portions 72, as shown in Figures 1, 2 and 4. The vertical wall 73 is not quite so long transversely of the base 11 as the end wall 23 of that base, as will be seen by reference to Figure 4. It is integrally connected to the inner sides of the inlet pipe connection 37 and outlet pipe connection 40 and with the inner wall of the projecting portion 35 forming chamber 36 and also between those parts on the lower side. It however has upwardly projecting portions 74, 75 above the inlet and outlet pipe connections with their inner edges on the arc of a circle spaced a short distance outwardly from the margin of the housing. It will be noted that these projections extend slightly above the upper edge of the end portions 24 and 25 of the end 23 of the base portion 11, as shown in dotted lines in Figure 4, the curved portion 20 of the end 23 of the base 11 being indicated by the dotted line 76 in Figure 2. The material of the wall 73 is not quite so thick above the dotted line 77 as it is below that line. A vertical flange or rib 78 extends upwardly from the central portion of the horizontal plate 71 and is integrally connected with the lower portion of the volute casing, as shown in Figure 4, and it extends to the outer margin of plate 71. The wall 73 has at its ends thickened or raised portions 79, 80, 81 and 82 provided with bolt holes matching corresponding bolt holes in the end of the base portion 11 whereby the parts may be bolted together. The upwardly projecting portions 74 and 75 are also provided with bolt holes 83 and 84 and bolts 85 pass through them and through the corresponding upper edge portions of the end wall 23. It will be noted by reference to Figure 1 that the bottom surface of the horizontal plate 71 is in the same horizontal plane as the lower edge of the downward projection 29 against which it abuts but that the lower surface of the enlarged portions of plate 71 are in the same horizontal plane as the lower surface of the downward projection 26 at the other end of the base 11 and thus these enlarged portions serve to support the end of the base which carries the pump when the device as a whole is placed on some other support. These enlarged end portions 72 furthermore are provided with bolt openings 86, (Figs. 2 and 4). A vertical strengthening rib 87 connects the projecting portion of the volute casing which forms the chamber 49 surrounding the shaft, and the lower horizontal portion 70 at the outer margin of the volute connecting its casing to the vertical wall 23, as shown in Fig. 1.

It will be observed that the structural combination between the motor and pump does not require or include the usual flexible coupling connecting them and thus the troubles usually incident to its use are avoided and the short rigid shaft extension used as a substitute for them has the additional advantages

of greatly reducing the space occupied by the combination and the number of working parts, and the resulting wear and chance for disarrangement, making it possible to move and ship the combination as an entity connected and ready for operation, dispensing with the usual supporting bearings for the shaft in the pump housing by supporting and centering that shaft through the action of the necessary bearings of the motor. In addition to the above noted advantages the structural arrangement is such that the motor and pump may be easily assembled and secured in co-operative relation and may be easily separated when desired. The detachable head portion 41 may be easily removed from the main part of the volute casing exposing the impeller by merely withdrawing the fastening bolts and without disconnecting any pipes. Furthermore the impeller may be removed from the end of its shaft by first taking off nut 57 and the impeller with the stub shaft 54 may be withdrawn together when the screw 59 is operated to disengage the projecting portion 32 of the motor shaft.

Although one specific embodiment of the invention is shown for purposes of illustration, it is not limited to the details shown beyond what is indicated in the following claims.

Having thus described the invention what is claimed as new and desired to be secured by Letters Patent is:

1. A centrifugal water pump comprising in combination a volute casing having integral inlet and outlet water pipe connections, an impeller secured to a drive shaft therein, a separate head portion comprising an end wall of the pump housing and the adjacent wall of the impeller casing spaced apart to form a water chamber between them and provided with an inlet port connecting said chamber with said inlet pipe connection of the volute casing and means for detachably connecting said head portion to said volute casing.

2. A centrifugal water pump comprising in combination a volute casing having integral inlet and outlet water pipe connections, an impeller secured to a drive shaft therein, a water chamber surrounding said shaft, a separate head portion comprising an end wall of the pump housing and the adjacent wall of the impeller casing, said walls being spaced apart to form a second water chamber between them, the head portion being provided with an inlet port connecting said second chamber with said inlet pipe connection of the volute casing, means for detachably connecting said head portion to said volute casing, and a vent pipe connection at the top of said volute casing in open communication with the upper end of at least one of said water chambers thus permitting the escape of air.

3. A centrifugal water pump comprising in combination a volute casing having integral inlet and outlet water pipe connections, an impeller secured to a drive shaft therein, a water chamber surrounding said shaft, a separate head portion comprising an end wall of the pump housing and the adjacent wall of the impeller casing spaced apart to form a second water chamber between them and provided with an inlet port connecting said chamber with said inlet pipe connection of the volute casing and means for detachably connecting said head portion to said volute casing, a vent pipe connection at the top of said volute casing in open communication with the upper end of at least one of said water chambers permitting the escape of air, part of the wall of the first mentioned chamber being extended longitudinally to form a stuffing box with packing therein surrounding said shaft.

4. A centrifugal water pump comprising in combination a volute casing having integral inlet and outlet water pipe connections, an impeller secured to a drive shaft therein, a water chamber surrounding said shaft, a separate head portion including an end wall of the pump housing and the adjacent wall of the impeller casing spaced apart forming a second water chamber between them and provided with an inlet port connecting said chamber with said inlet pipe connection of the volute casing and means for detachably connecting said head portion to said volute casing, the vent pipe connection at the top of said volute casing in open communication with the upper end of at least one of said water chambers permitting the escape of air, part of the wall of the first mentioned chamber being extended longitudinally forming a stuffing box with packing therein surrounding said shaft, a lantern gland between the ends of said packing and a pipe connecting said gland to the volute of the pump to water seal the stuffing box.

5. A centrifugal water pump comprising in combination a volute casing having integral inlet and outlet water pipe connections and an impeller secured to a drive shaft therein, a separate head portion comprising an end wall of the pump housing and the adjacent wall of the impeller casing spaced apart to form a water chamber between them and provided with an inlet port connecting said chamber with said inlet pipe connection of the volute casing and means for detachably connecting said head portion to said volute casing, said inlet pipe connection projection outwardly in a radial direction from the outer margin of the volute and including a chamber having an inlet for water and a lateral opening in its radial side facing the head portion and the said head portion having a radial projecting portion in contact at one side with said inlet connection and having an opening

in that side registering with said opening in said chamber.

6. A centrifugal water pump comprising in combination a volute casing having integral inlet and outlet water pipe connections, an impeller secured to a drive shaft therein, packing for said shaft, an integral projecting portion on said casing forming a passageway across the top of the volute at its highest point having a vent opening over the volute and extending radially inwardly of the volute casing terminating in a chamber surrounding the drive shaft and having an opening in its outer wall containing said packing through which said shaft passes, a separate head portion including an end wall of the pump housing and the adjacent wall of the impeller casing, said walls being each spaced apart forming a second water chamber between them, said head portion being provided with inlet ports connecting said second water chamber with said inlet pipe connection and with said passageway across the top of the volute casing and means for detachably connecting said head portion to said volute casing.

7. Pumping apparatus of the character described including in combination a plate-like base having an open upper side, means for supporting one end of said base, the other end of said base having a vertical surface, a pump secured against said surface having means constituting a support for this end of the base, a motor removably secured on the open upper side of said base having a rotary shaft supported in fixed position by bearings in said motor and projecting therefrom for a material distance, and means for securing the impeller in said pump to said shaft whereby it will be supported and rotated by said shaft.

8. Pumping apparatus of the character described including in combination a base, means for supporting one end of said base, the other end of said base having a vertical surface, a pump secured against said surface having means constituting support for this end of the base, a motor detachably mounted as a unit on said base having a rotary shaft supported in fixed position by bearings in said motor and projecting therefrom for a material distance, and means for securing the impeller in said pump to said shaft whereby it will be supported and rotated by said shaft, the projecting portion of said shaft being composed of two aligned sections detachably but rigidly secured together, the outer section entering said pump.

9. Pumping apparatus of the character described, comprising in combination, a centrifugal pump comprising a rotor and a housing having a head, said housing being provided with pipe connections for inlet and discharge pipes and having an inlet chamber, said head having a radial extension at the lower portion

of the periphery thereof provided with a port affording communication between said inlet connection and chamber, a base having a vertical end surface adapted to fit against a corresponding surface on said housing, means to secure the housing against said surface, and a motor mounted on top of said base having its shaft in alignment with the axis of the rotor of the pump.

10. Apparatus of the character described including in combination, a base having a vertical surface at one end thereof and supporting flanges at the other end, a motor on said base, a centrifugal pump aligned with
15 and driven by said motor and having a vertical surface, and means securing said pump to said base with said surfaces in contact, said pump having a plate like portion with thickened end portions providing the support for
20 the pump end of the base, and inlet and outlet pipes entirely free of said base.

11. A centrifugal pump comprising in combination a casing having a separable head closure, an impeller, two walls around the
25 hub of said impeller within the casing forming an impeller housing, one of said walls being integral with said head closure and spaced from the end thereof providing an inlet chamber, a second chamber at the other
30 side of said hub in communication with the inlet chamber outside the periphery of said housing, whereby the pressure on the opposite ends of the impeller hub is balanced.

In testimony whereof I hereunto affix my
35 signature.
